UNITED STATES PATENT OFFICE.

EDWARD EBI, OF CEDAR RAPIDS, IOWA.

BRAKE-ROD.

SPECIFICATION forming part of Letters Patent No. 246,101, dated August 23, 1881.

Application filed March 30, 1881. (Model.)

To all whom it may concern:

Be it known that I, EDWARD EBI, of Cedar Rapids, in the county of Linn and State of Iowa, have invented a new and Improved Brake-Rod, 5 of which the following is a specification.

The object of my invention is to facilitate operating all the brakes of a train simultaneously from the locomotive.

The invention consists in a rod passing 10 through journal-bearings on the under side of the car, and provided at the ends with pivoted connecting-bars having spring-catches for keeping them united, which connecting-bars are locked to the brake-rods by means of a 15 lever pivoted to the connecting-bar and passing into notches of a loose and a rigid circular plate on the brake-rod, so that all the brake-rods of the several cars of a train will be revolved together and the brake-shoes will be 20 drawn against the wheels simultaneously.

In the accompanying drawings, Figure 1 is a side elevation of two connected ends of my improved brake-rod. Fig. 2 is a plan view of the same. Fig. 3 is a cross-sectional elevation 25 of the same on the line $x-x$, Fig. 1. Fig. 4 is a cross-sectional elevation of one of the connecting-bars with its clamp and spring-catch.

Similar letters of reference indicate corresponding parts.

The rods A A pass through journal-bearings B B, suspended from or attached to the under side of the car, so that these rods can be rotated freely. A circular plate, C, with a notch, D, and provided with jaws E, is loosely 30 mounted on the end of the rod A, and a bar, F, is pivoted to the jaws E. A circular plate, G, with a series of notches, H, in the circumference, is rigidly mounted on the bar A, adjoining the plate C; and if a latch-lever, J, 35 pivoted on the bar F, is passed into the notch D of the plate C and into one of the notches H of the plate G, the two plates G and C will be locked to each other. A spring, K, holds the 40 latch-lever J in its various positions. A U-shaped clamp, L, is attached to each bar F in such a manner that this bar rests against one 45 of the shanks and against the transverse piece M of the clamp L, as shown in Fig. 3.

A spring-latch, N, with an outwardly-bevelled end, is attached to that shank of the clamp L against which the bar F rests, so that 50 this latch passes across the clamp, and its point is adjoining the other shank.

The brake-chain I is attached to the bar A, and will be wound upon the same when the 55 bar is rotated by suitable mechanism.

The operation is as follows: Ordinarily the connecting-bars F hang down from the ends of the bar A; but when two cars have been coupled one bar F is passed into the U-shaped 60 clamp L of the other, and is retained in the same by the spring-latch N, this bar F pressing the spring of the latch N inward as it enters into the clamps L. If the cars are uncoupled, the bars F simply slide out of each 65 other's clamps, and then hang from the end of the rods.

The rods A of all the cars of a train can be connected in the manner described above. If the latch-lever J is raised, the connecting-bars 70 F will not be rotated, and thus any number of cars can be disconnected, if desired.

The rod A of the locomotive is rotated by means of some suitable mechanism on the locomotive, and the movement of this bar A is 75 transmitted to the others in the manner shown and described.

Having thus fully described my invention, I claim as new and desire to secure by Letters Patent—

1. The combination, with the rod A, journaled on the under side of a car, of the notched circular plate C, the pivoted connecting-bar F, the notched circular plate G, and the latch-lever, J, pivoted to the connecting-bar F, substantially as herein shown and described, and for the purpose set forth.

2. The combination, with the rod A, journaled on the under side of a car, of the connecting-rod F, pivoted to a notched circular 90 plate, C, loosely mounted on the end of the rod A, of the notched circular plate G, rigidly mounted on the rod A, and of a U-shaped clamp, L, attached to the connecting-rod F and provided with a spring-latch, N, substantially as herein shown and described, and for the purpose set forth.

3. In a brake-rod connection, the connecting-bar F, constructed substantially as herein shown and described, with an U-shaped clamp, 95 L, provided with a spring-latch, N, attached thereto, as and for the purpose set forth.

EDWARD EBI.
